[57] CLAIM

The ornamental design for a bread baking appliance, as shown and described.

DESCRIPTION

FIG. 1 is a perspective view taken from the top, front, and left side of a bread baking appliance;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is another perspective view taken from the top, front, and left side thereof showing the lid unit in an open position.
